UNITED STATES PATENT OFFICE.

EDWIN N. LIGHTFOOT, OF NEW YORK, N. Y.

ELECTRIC HEATER.

1,200,630

Specification of Letters Patent. Patented Oct. 10, 1916.

Application filed February 6, 1913. Serial No. 746,586.

To all whom it may concern:

Be it known that I, EDWIN N. LIGHTFOOT, a citizen of the United States, residing at New York, in the county of New York and State of New York, have invented new and useful Improvements in Electric Heaters, of which the following is a full, clear, concise, and exact description, reference being had to the accompanying drawing, forming 10 a part of this specification.

My invention relates to improvements in electric heaters.

One object of the invention is to provide a heater having two heating plates heated 15 by a common group of heating units arranged between the same, said plates being held together by means located between the heating units, whereby said plates are maintained in proper spaced relation at all times 20 regardless of expansion and contraction.

Another object of the invention is to provide a novel construction of a two plate heater employing a plurality of heating units, said plates being held together independently of said units whereby the latter 25 may be removed from the heater if it becomes necessary to replace a defective unit.

An additional object of the invention is to provide an improved electric table stove 30 which shall be neat, ornamental and compact, having removable interfitting parts which may be assembled in various different ways to perform a variety of functions.

In the accompanying drawings I have 35 illustrated several embodiments of the invention. Various other forms may be devised however which fall within the scope of the invention.

Figure 1 is a top plan view of the heating 40 element of an electric stove, with one of the heating plates removed. Fig. 2 is a longitudinal sectional elevation thereof. Fig. 3 is a transverse sectional elevation thereof. Fig. 4 is a side elevation, partly in section 45 of the assembled stove. Fig. 5 is a side elevation of certain parts of the stove assembled in a different way. Fig. 6 is an end view on an enlarged scale of the handle of the heater element of the stove. Fig. 7 is a 50 plan view of a modified form of heater. Fig. 8 is a sectional elevation thereof. Figs. 9, 10, 11, 12, 13 and 14 are sectional elevations of further modified forms of heaters.

The preferred form of electric stove which 55 is shown assembled in Fig. 4 comprises a suitable stand 1 formed preferably from a

single piece of sheet metal, and provided with legs 2, said legs consisting of angle sections preferably welded or riveted to the upwardly turned flange 3 of the base. 60

The base supports a pan 4, the latter having a handle 5 and having an upper enlargement 6 forming a shoulder. Said shoulder is adapted to support the heating element or heater, the latter comprising a bottom 65 plate 7 having a vertical flange 8 and a top plate 9 having a vertical flange 10, said plates fitting together as shown in Fig. 3, and having their flanges integrally united to form a water tight construction. Said heater 70 has also a handle 11 within which the circuit terminals are located, said handle being hereinafter described more fully.

A sheet metal cover 12 having a downwardly extending flange 13 is also provided 75 said cover having a handle 14. A broiling and toasting screen 15 is shown in Fig. 4 arranged within the pan and an aluminum plate 16 is shown in Fig. 5 resting directly on the heater to provide a suitable heating 80 surface for griddle cakes and the like. In Fig. 5 the pan has been removed, the electric heater resting directly on the stand 1.

The heating units, by which the two heating plates 7 and 9 are heated, each have in 85 the preferred form a sheet metal channel 17 on the bottom of which a strip of mica 18 is placed. A slotted resistance ribbon or resistor 19 of less width than the mica is then placed over said mica and a second 90 sheet of mica 20 laid thereon. A second resistor 21 is superimposed on the mica 20 and an additional strip of mica 22 placed thereover. A strip of metal or cover plate 23 is placed over said mica 22 and the 95 sheet metal flanges of the flexible channel 17 are bent over to firmly compress the layers of mica and resistance ribbon and hold these elements in place. The resistors are thus in close proximity to the metal walls of the 100 channel thereby establishing good heat conducting relations between the two.

The upper resistor in each unit is connected at its opposite ends as shown in Fig. 1 to an adjacent resistor whereby all four 105 upper resistors are connected in series. In a similar manner all of the lower resistors are connected in series. The total resistance of the upper resistors is different from the total resistance of the lower resistors, and 110 said resistors being independent of each other it is possible to obtain two heats by

using one or the other. By connecting both resistors in parallel a third heat is obtained, these connections being made with an external circuit, and controlled by any well known device suitable for the purpose. The connection between the adjacent ends of the resistors is effected as shown in Fig. 2 by U shaped metallic strips 24 and 25 said strips being suitably insulated by mica. The ends of two of the resistors are of reduced width and are folded over to form a pair of terminals 26 for the upper set of resistors. A similar pair of terminals 27 is provided for the lower resistors as shown in Fig. 1.

The heating plates 7 and 9 are spaced apart by metallic bars or strips 28 as shown in Fig. 3. Said plates are integrally united to said bars preferably by electric-welding. Accordingly they are spaced apart the proper distance to permit the heating units to be located between said plates and the proper spacing is maintained irrespective of distortion due to expansion and contraction. Accordingly the walls of the channel are always in close proximity to the heating plates and a good thermal conducting relation is maintained. The bottom of each channel may be electrically-welded to the adjacent heating plate if desired. With such a construction the thermal conductivity is very good. The heating units are not removable in such a case however and hence under some circumstances it is desirable not to weld said units but to leave them unattached whereby they may be slipped in and out from between the heating plates to provide for occasional renewals.

It will be seen that either heating plate may be used as the upper surface of the heater by simply inverting the latter. The flanges form a pan whereby the heater may be used as a frying pan and for similar purposes. The flat base may be used for griddle cakes or the like, though I prefer to use an aluminum plate in addition as shown in Fig. 5. With the arrangement shown in Fig. 4 the stove may be used for broiling purposes, the meat being placed on the screen 15, the cover 12 providing an air space above the upper surface of the heater, thereby minimizing loss of heat in an upwardly direction. The stove may also be used for heating water, coffee, etc., by simple resting the vessel thereon. It may also be used for a great many other kinds of cooking and for various purposes which will readily suggest themselves.

The circuit connections are made within the handle 11 said handle having an internal sheet metal tubular member 29 the outer end of which is provided with a second metallic tube 30 in position within the handle. Said tube as shown in Fig. 6 is provided with a slot 31 which guides the plug mem-

ber of the separable connector (not shown). The circuit terminal pins 32 are carried by the head 33 and are electrically connected to the terminal extensions 26, 27 previously described.

In Figs. 7 and 8 a modified form of heater is shown in which a pair of heating plates 35, 36 are each electrically-welded to a plurality of spacers 37 in a manner similar to that previously described. The heating units 38 may be slipped in or out of their inclosures, each heating unit being provided with a pair of terminals 39, 40 whereby each unit constitutes an independent heater.

The construction in Fig. 9 is quite similar to that just described except that the heating plates are welded together at their edges thereby forming a water-tight enclosure slightly different from the preceding

The construction in Fig. 10 is similar to the preceding figures except that the spacers 37 are of varying widths, the middle spacer being wider than the other two. This provides for a more uniform distribution of heat. The middle spacer may be provided with an opening 39 if desired to permit the upward circulation of liquid therethrough.

In Figs. 11 and 12 the heating plates are spaced apart by spacers 40 of greater thickness than the thickness of the heating units. Said spacers may assume many different forms, a number of modifications being illustrated. The spacers in Fig. 12 are hollow and provided with openings therethrough registering with corresponding openings in the heating plates to facilitate circulation. Fig. 13 is somewhat similar to the above figures and will be readily understood.

In Fig. 14 the heating units are removable and are held in close proximity to the upper and lower heating plates by T shaped retainers integrally united to said plates.

The various forms of heaters described may be used within oven walls for example and are so designed that the individual units may be replaced when necessary. They may also be used in various other relations other than in ovens and table stoves.

In general I do not desire to limit myself to the constructions described and illustrated but desire to cover within the scope of the appended claims suitable equivalent means wherever such means fall within the scope of the appended claims.

Having thus described my invention, what I claim as new and desire to secure by Letters Patent of the United States is:

1. An electric heater comprising a plurality of electric heater units spaced apart, relatively thin metallic heat dissipating plates in contact with opposite sides of said units, and spacers of a thickness substan-

- 5 tially equal to the thickness of said units located between said units to which said plates are integrally united so that said units are held in close thermal contact with both of said plates to provide a reversible heater having two heating surfaces.
2. An electric heater having heating surfaces of substantial area on opposite sides thereof so that the heater is reversible, said 10 heater being provided with a pair of metal heat dissipating plates spaced apart, electric heating units between said plates and integrally united to one of them and spacers between said units to which both of said 15 plates are united, the periphery of said plates being integrally united to form a water-tight heater.
3. An electric heater having heating surfaces of substantial area on opposite sides 20 thereof so that the heater is reversible, said heater comprising a pair of spaced, metal, heat dissipating plates, electric heating units between said plates and integrally united to one of them, and spacers between 25 said units to which both of the plates are united, said spacers being of a thickness substantially equal to the thickness of the units, the edges of the plates being integrally united to form a water-tight heater.
- 30 4. A double surface electric heater comprising a pair of heat dissipating metal plates, a plurality of substantially parallel heating units arranged between said plates and integrally united to one of them, a plurality of substantially parallel metal elements arranged between said heating units and of a thickness substantially equal to the thickness of said units, both of said plates being integrally united to said metal elements whereby the other plate is held in close contact with said units, said plates having flanged peripheries, one of which fits within the other, said flanges being integrally united to form a water-tight joint.
- 45 5. In an electrical heater, in combination, a plurality of substantially parallel, spaced apart, heating units, each unit comprising a sheet metal resistance carrier consisting of a channel having its flanges bent over, and 50 a resistance inclosed within said channel and insulated therefrom, a plurality of substantially parallel metal bars arranged in the spaces between said units and a pair of heat dissipating plates arranged on opposite sides 55 of said units, one of said plates being integrally united to one surface of each resistance carrier and both plates being integrally united to said bars, whereby the other plate is also held in close heat conducting 60 relation with the opposite surface of said units.
6. In an electric heater in combination, a plurality of substantially parallel heating units spaced from each other, a plurality of substantially parallel metal channels arranged between said heating units, and of a thickness substantially equal to the thickness of said units, and a pair of metallic plates on opposite sides of said heating units, said plates being electrically welded 65 to said channels, said channels being slightly compressible whereby said plates may be pressed into close contact with said units, regardless of slight initial variations in the thickness thereof.
7. A double surface electric heater having a pair of parallel weldable metallic heat dissipating plates and metallic spacers located between said plates for holding the same in spaced relation, said spacers being 70 welded to said plates and mechanically incased heater units located between said heating plates and between said spacers, said units having their casings welded to 75 one of said heating plates.
8. An electric heater having a pair of weldable, metallic, heat dissipating plates arranged parallel to each other, spacers located between said plates for holding the same in spaced relation, and a heater unit 80 located between said plates and between said spacers, said heater unit having a resistor and a resistance carrier incasing said resistor, said resistance carrier consisting of 85 weldable sheet metal and being welded to one of the aforesaid heat dissipating plates.
9. A flat electric heater plate having two opposite heating surfaces so that the plate is reversible, said plate comprising a plurality of electric heater units, a plurality of 90 spacers between the edges of said units, weldable metallic heat dissipating plates on each side of said units, said plates having their peripheries welded together to form a water-tight inclosure and being welded to 95 said spacers to hold said heater units in close thermal contact with the heat dissipating plates.
10. An electric heater having two opposite heating surfaces so that the heater is 100 reversible, said heater comprising two relatively thin metallic heat dissipating plates spaced apart and integrally united at their edges to form a water-tight inclosure and 105 metallically incased electric heater units between said plates, said units having their casings integrally united to said plates.
- In witness whereof, I have hereunto subscribed my name in the presence of two witnesses.

EDWIN N. LIGHTFOOT.

Witnesses:
GEO. B. JONES,
G. P. BROCKWAY.

It is hereby certified that in Letters Patent No. 1,200,630, granted October 10, 1916, upon the application of Edwin N. Lightfoot, of New York, N. Y., for an improvement in "Electric Heaters," errors appear in the printed specification requiring correction as follows: Page 3, line 45, claim 5, for the words "In a electrical heater" read *In an electric heater*; same page, line 81, claim 7, for the word "mechanically" read *metallically*; and that the said Letters Patent should be read with these corrections therein that the same may conform to the record of the case in the Patent Office. *

Signed and sealed this 21st day of November, A. D., 1916.
